UNITED STATES PATENT OFFICE.

ROBERT CUMMING ANNAND, OF SOUTH SHIELDS, ENGLAND.

ROTARY WEB-PRINTING MACHINE.

No. 834,602

Specification of Letters Patent.

Patented Oct. 30, 1906.

Application filed March 18, 1905. Serial No. 250,710.

To all whom it may concern:

Be it known that I, ROBERT CUMMING ANNAND, printers' engineer, a subject of the King of Great Britain and Ireland, residing in South Shields, England, have invented certain new and useful improvements in or Relating to Rotary Web-Printing Machines, of which the following is a specification.

This invention relates to rotary web-printing machines; and its chief object is to provide machinery which will produce various lengths of printed sheets that are folded and severed after the web has been printed.

Several attempts have been made with the object in question; but up to the present all such attempts have failed to provide a practical working machine. As the result of much study and experiment I have succeeded in providing a practical machine capable of producing different sizes of products very efficiently at high speeds.

While the invention has been designed chiefly with the main object above mentioned, certain of the features or elements of the improved apparatus, though specially useful in machinery for dealing with various lengths of printed sheets, can be employed with advantage in other types of rotary web-printing apparatus, and such employment is included in the present invention.

In order to get a rotary web-machine to print and fold sheets varying in length, it has hitherto been found necessary to cut the web into sheets before printing. This type of machine has many defects, chiefly due to the cutting of the sheets before printing, as these sheets have to be carried through the machine by grippers, tapes, and suction mechanism, and good printing and accurate folding cannot be effected except at a very slow speed.

The present invention provides a practical machine which will produce various-sized products both in length and breadth.

To illustrate the invention, I will describe, with the aid of the accompanying drawings, one example of machine embodying the improvements and then certain modifications and details. The expression "delivery mechanism" in accordance with the usual practice includes all mechanism for folding, cutting, or performing other operations on the web after printing.

In the drawings, Figures 1 to 14 illustrate a machine arranged or adapted to print the web on both sides, slit it longitudinally,

associate and fold the slit web to four-ply, sever the four-ply into sheets, and fold same into sixteen or thirty-two page products. Fig. 1 is a diagrammatic side elevation of the machine. Figs. 2 and 3 are respectively a front elevation and a side view, both partly in section, of the mechanism for looping the web being printed. Fig. 4 is a detail view of the cam for this looping mechanism. Fig. 5 is a part side elevation of the delivery mechanism up to and including the fold-former 106. Fig. 5^a is a corresponding and continuation view including the perforating-cylinders 108 and tapes 112. Fig. 6 is a plan of folder-bars, associating-rollers, and fold-former; Fig. 7^a, a corresponding view of Fig. 5^a. Fig. 7 is a rear elevation of Fig. 5. Fig. 8 is a front elevation of longitudinal slitting mechanism. Fig. 9 is a part side elevation of the remainder of the delivery mechanism. Figs. 10, 11, 12, and 13 are sectional views of the mechanism for severing and further folding the longitudinally-folded web and showing successive stages of the folding operation, Figs. 10, 12, and 13 being on an enlarged scale. Fig. 14 is a corresponding plan view. Figs. 15 and 16 are diagrams, respectively, in side and part front elevation of a modified folding and delivery mechanism; and Fig. 17 is a sectional detail view illustrating means for adjusting the operative members of the folding-cylinders 208 and 212. Figs. 18 to 20 are part-diagrammatic views corresponding to Figs. 15 and 16, showing the product in various positions. Figs. 21, 22, and 23 are respectively a cross-section, end elevation, and part longitudinal section of improved pasting mechanism.

1 is the reel of paper, mounted as usual. 95 The web 2 is first introduced between drawing-rollers 3 4. The roller 3 is driven by gear 6, meshing with a gear 5 on the same shaft through the medium of gears 7 and 8 and a gear 9 on the shaft of the lower stereo-cylinder. Gear 6 is carried on the adjustable quadrant 10. The gear 5 is interchangeable with other gear-wheels to enable the speed of the drawing-rollers to be varied, so as to supply the length of paper required during one revolution of the printing-cylinders, according to the size of sheet to be printed. The web next passes around a fixed guide-roller 11, under a looping-roller 12, and then between the stereo-cylinder 13 and impression-cylinder 14, which print one side of the web. The web then passes between the registering-

roller 15 and fixed guide-rollers 16 17 and thence between the upper stereo-cylinder 18 and impression-cylinder 19, which "perfect" the printing—*i. e.*, print the other side of the web. Registering-roller 15 is adjustable in any ordinary or suitable way—as, for instance, by means of a rack and pinion 20 21 at each side of the machine, operated by a hand-wheel 22 on the shaft carrying the pinions. When the machine is printing the smallest size of sheet, the web passes to the printing-couple 18 19 in a straight line; but when larger sizes are being produced roller 15 is drawn in to a corresponding extent, so as to form a loop in the web, and so insure that the printing-couple 18 19 shall print the second side of the web accurately opposite the matter printed by the first printing-couple 13 14. The rollers 16 17 are so arranged that whatever amount of loop the registering-roller 15 is set to produce the web is kept from rubbing on the cylinders 13 14 and 18 19.

From cylinders 18 19 the web passes over a looping-roller 23, then under a stationary guide-roller 24, and thence preferably to feeding-out mechanism driven by gearing which can be changed so as to regulate the "flow" of the paper to the delivery mechanism of the machine. This feeding-out mechanism prevents undue strain on that part of the web which is being printed and also that part manipulated by the looping-rollers. It consists of a feeding-out roller 25 and endless margin-tapes 26, passing around idle rollers 27 28 and also around adjustable tension-pulleys 29, mounted at each side of the machine. The roller 25 is driven by an interchangeable gear-wheel 30, mounted on an adjustable quadrant-arm 31 and meshing with a gear 32 on the shaft of roller 25 and with a gear 33, which in turn meshes with the gear-wheel 56, referred to later. The tape-roller 27 is geared to the roller 25 by toothed wheels 34 and 35 on the respective shafts of these rollers. From this feeding-out mechanism the web passes to the delivery mechanism, described later.

The respective stereo and impression cylinders 13 14 and 18 19 are geared together as usual, their pitch-circles being equal to the longest sheet the machine is built to print. The distance between the points of contact of the respective couples should be equal to the length of the smallest sheet to be produced. The dimensions of the stereo-cylinders may be such as to take in four pages in the circumference of each cylinder and four pages in the length.

The looping-rollers 12 and 23 are carried by bearings 36, attached to vertical side tubes or rods 37 37, (see Fig. 2,) whereby they are coupled together, so that an intermittent vertical reciprocating motion can be given to them to loop up and give out the surplus

web supplied by the drawing-rollers 3 4 when the machine is printing smaller lengths of sheet than the maximum.

I have found that it is essential to the successful practical operation of the machine that during the time the blank portions of the printing-cylinders are passing the printing-point in printing sizes less than the maximum the web must be first gradually arrested before the printing-couples, then slightly retracted, and then restarted forward at a gradually-increasing speed, so as to be traveling at the same surface speed as the printing-surfaces when these again reach the printing-point and grip the web. The web is thus alive when it is gripped between the printing and impression surfaces, and an even and regular feed is insured, preventing the strain and tearing which would occur if the web were arrested during the period in question, and thus subjected to sudden starting and stopping. At the same time the slight retraction of the web prevents wastage of paper on large margins. To attain the object mentioned, I operate the looping-rollers in such manner that their speed during that part of their motion which corresponds to the passage of the blank portions of the stereo-cylinders opposite the printing-point first increases gradually to a maximum, so that the web is gradually arrested and slightly drawn back, whereupon, and still during the passage of the blank parts opposite the printing-point, the speed of the looping-rollers in the opposite direction is gradually increased, so as to gradually feed the web forward until when it is again gripped between the printing and impression surfaces it is traveling at the proper surface speed. To attain this result, I employ special cams, as described later.

The tubes 37 terminate at bottom in blocks 38, which slide in grooves 39 in plates 40, attached to the framework at each side of the machine. 41 41 are gear-wheels mounted in bearings 42 42 near the lower ends of the tubes 37 and driven by the transverse shaft 43 through the gears 44 44 on this shaft, which receives its motion from the stereo-cylinder 13 through the gears 7 8 9. The gears 41 make one revolution for each revolution of the printing-cylinders. On the inside face of each gear-wheel 41 is fixed a speed-cam 45. Cam-rollers 46 46 are carried on the sliding blocks 38 and are held in working contact with the respective cams in any suitable way—for example, by springs 47 47 coiled on the tubes 37 and bearing against fixed abutments on the frame. Instead of employing springs the rollers 46 may work in cam-grooves in the face of the cam-plates.

The change-gear of the drawing-rollers 3 4 and that of the roller 25 are set to feed the proper amount of paper to give the right length of sheet required.

When the machine is printing the maxi-

mum size, the looping-rollers 12 and 23 are not required to loop up any surplus feed of web. The cams 45 are then replaced by plain circular disks, so that the looping-rollers are kept in a stationary position. When, however, a small size has to be printed, the looping mechanism is used as follows:

Supposing, for example, that the full capacity of the machine is a sheet forty-four inches 10 in length or "cut-off" and it is required to produce a sheet thirty-three inches long, in this case only three-fourths of a full sheet is being printed, and there will consequently be one-quarter of the stereo-cylinders 13 18 15 bare. The cams 45 to be secured on each side of the machine will be so shaped and arranged as to cause the looping-rollers to perform the variable motion before described 20 during the quarter-revolution corresponding to the passage of the bare quarter of the printing-cylinders past the printing-point—that is to say, during this quarter-revolution they will descend with a speed which gradually increases to a maximum, so as to 25 gradually arrest and slightly retract the web, and will then rise with a gradually-increasing velocity, so that at the end of the quarter-revolution of the printing-cylinders the web will be traveling forward at the proper 30 speed to be nipped between the impression-cylinder and the leading edge of the printing-surface, which surface has again reached the printing position. In this way it will be understood that after the rear end of printing- 35 surface has passed the impression-cylinder the web follows it for a short distance, but gradually comes to a standstill. Then as the cam travels farther around the web is drawn slightly back and then gradually 40 started forward again until it attains the proper surface speed, when the leading edge of the printing-surface reaches the printing-point. During the descent of the looping-rollers the bottom roller 12 takes up the 45 paper fed in by the drawing-rollers 3 4, and the simultaneous descent of the top roller 23 gives up paper to the succeeding mechanism at the same uniform speed as before. During the rise of the looping-rollers while the printing-couples are making the three-quarters of 50 their revolution in which the impression takes place the roller 12 gives up paper and the roller 23 simultaneously loops up the same amount of paper, so that the web travels on from the printing-couples at the same uniform speed at which it is fed to them.

The proper shaping of the cams 45 is a matter of the highest importance for the efficient working of the machine, and I have 55 therefore shown in Fig. 4 a practical example of the way in which a circular disk should be cut to form a cam for a smaller size. The example shown is a cam for use when printing a very usual length of sheet—viz., thirty-six inches and assuming the largest length of

sheet to be forty-four inches. This cam provides for a maximum drop or descent of the cam-roller to the extent of 3.2724 inches, the cam-roller being supposed of two inches diameter. For sizes intermediate between forty-four-inch and thirty-six-inch lengths, for example, the cams may be shaped to give the following maximum drops of the cam-rollers:

Length.	Drop.	75
44 inch.	Nil, (circular disk.)	
43 inch.	.4886 inch.	
42 inch.	.9545 inch.	
41 inch.	1.3977 inch.	80
40 inch.	1.818 inch.	
39 inch.	2.2157 inch.	
38 inch.	2.5908 inch.	
37 inch.	2.9431 inch.	
36 inch.	3.2724 inch.	85

For convenience it is advisable in practice to make the radius of the highest part of the cam equal to the radius of the printing-cylinders. Fig. 4 and the above explanation will enable those skilled in the art to produce cams for any other desired sizes of sheet. Evidently in machines in which more than two printing-couples are employed the looping-rollers may be disposed respectively in front of the first couple and after any subsequent couple. The motion is preferably imparted to the printing-couples by a vertical shaft 48 through the medium of bevel-gears 49 50.

The printed web after it passes the feeding-out mechanism already described is carried over a guide-roller 51 and thence to apparatus for slitting it longitudinally. As the speed of the web varies according to the size of product, this apparatus must be capable of efficiently slitting webs traveling at different speeds. To this end it comprises a smooth roller 52, driven by a vertical shaft 53 through the medium of bevel-gear 54 55 and gear-wheels 56 57. The smooth roller 52 has a groove 58 cut in the middle, in which revolves a circular cutter 59 on a pivoting arm 60, so as to be adjustable, and which slits the web lengthwise into two parts. The margins of the two portions of the slit web are pressed upon the roller 52 by four adjustable rubber disks 61, mounted on arms 62, carried on a transverse shaft 63.

The two parts of the slit web are next passed under and around the angle-bars 64 65 (see Fig. 6) or an equivalent device, the one half being turned to the left over the bar 64 and the other to the right over bar 65. From these bars the respective halves pass over the registering guide-rollers 66 67 and thence to the associating-rollers, described later. To enable the center margins of the slit web to pass direct onto the nose or center of the fold-former 106, the angle-bars 64 65 are preferably made adjustable. For this 130

purpose the nose or junction of these bars is carried by an arm or extension 68, supported from the shaft 63, as follows: On the shaft 63 is a sleeve 69, cast with an extension 70. A bolt 71 is passed down through 70 and through a long slot 72 in 68 and is secured by a nut. 73 is a screw-spindle fitted with a hand-wheel and passed through the end of 68 and screwing into the extension 70. The opposite ends of the angle-bars are supported from a transverse bar 74 by arms 75, provided with slots 76, guided and secured by bolts 77, passed through said slots and through lugs 78 and secured by nuts. By slightly slackening the nuts on the bolts 71 and 77 and turning the screw 73 the angle-bars can be correspondingly adjusted longitudinally as required to suit the width of web.

The registering-rollers 66 67 are carried in arms 79 80 at each side of the machine, the pairs being respectively mounted on shafts 81, so as to be adjustable toward and away from the angle-bars, this adjustment being effected by means of hand-wheels 82 82, screwing on the ends 83 83, connected to the shafts 81 by levers 84, the bosses of the hand-wheels 82 bearing against lugs 85 85, bolted to the frame, and springs being coiled between the lugs 85 and fixed collars on the rods 83, as shown.

To prevent the turning bars or devices from smearing the freshly-printed paper, I prefer to employ hollow non-perforated bars, as shown in the drawings, and to heat them by passing the products of combustion from Bunsen or other burners through them or by electric resistances. In the arrangement shown downwardly-directed tubes 86 87 are attached to the angle-bars 64 65. To the bottom of each of these tubes is fitted a Bunsen burner 88 89, the hot gases from which fill the angle-bars and heat the same, so that they do not injure the printed paper to the same extent as they would in the cold state. At the opposite ends of the turning bars are smaller upward tubes 90 91, which act as chimneys and allow the gases to escape slowly, thereby maintaining the circulation of the gases in the tube. Instead of heating the angle-bars by burners I may circulate steam, hot water, or other heating agent through them or dispose electric resistances in them; but it will be found more convenient as a rule in printing-offices to use Bunsen burners as described.

From the rollers 66 67 the slit half-webs join each other at the associating-rollers 92, 93, and 94, Fig. 7. The half-webs are thus laid one above the other to form two-ply of paper. Rollers 92 and 94 are each provided with two adjustable friction-disks 95 96 to press the paper upon them and are driven from the gear 56 through a gear 97 on a shaft 98, carrying a bevel-wheel 99, gearing with a bevel-wheel 100 on the shaft of roller 94. At

the opposite end roller 94 carries a gear 101, meshing with a gear 102 on shaft of roller 93 and which drives a corresponding gear 103 on roller 92 through a gear 104. 105, Fig. 7, represents tapes which pass the two-ply web onto the fold-former 106, which, assisted by the drawing-roller 107 107, Figs. 5^a and 6, doubles it longitudinally into four-ply. The web then passes down to the perforating-cylinders 108 108, one of which is fitted with one or more 75 gapped perforating-blades 109 (two are shown) and the other with corresponding bolsters 110. In the example under description the diameter of these cylinders is such that their surface speed is equal to that of 80 the web for the smallest sheet the machine will produce, and they are spaced apart to allow the web to pass through unhindered. Thus when the perforator 109 and bolster 110 are in contact and nip the web this is 85 slightly looped between the rollers 107 and cylinders 108 when the machine is producing any size larger than the minimum length. The perforated web then passes between another pair of drawing-rollers 111, 90 which run somewhat faster than the surface speed of the web for the largest-sized sheet. Consequently any loop previously formed between 107 and 108 is pulled out and the product straightened. From the rollers 111 the 95 perforated web is carried down by margin tapes 112 to collecting and folding mechanism.

It will be understood that instead of entire cutting or perforating cylinders portions 100 thereof or rotary parts carrying the cutting or perforating members may be employed in any of the arrangements above described. I include such devices in the expression "cylinders." This mechanism comprises four 105 cylinders 113, 114, 115, and 116 geared together and of such diameter that their surface speed is greater than that of the web in the machine, the last cylinder 116 being twice the diameter of the others. Cylinder 113 has a set of spring-controlled collecting-grippers 117, operated by a fixed cam 118 on the framework and a movable cam 119, through the medium of a roller 120, carried by the gripper-rod crank 121, the spring 122 115 being connected to the other arm of the gripper-rod crank. Cylinder 113 has also a folding-blade 123. Cylinders 114 and 115 have each a rubber nipping projection 124 and 125, and cylinder 116 has two diametrically opposite folding gripper-blades 126 127, arranged to co-operate with the folding-blade 123 of cylinder 113 and operated by a fixed cam 128 on the framing through rollers 129 130 and springs 131 132.

Cam 119 is carried on an arm 133 and is preferably adjustable thereon by a bolt and segmental slot 134, as shown. The arm 133 forms one member of a kind of locking lever, being pivoted to the frame at 135 and carry- 135

ing an extension-lever 136, fitted with a roller 137, adapted to be held upon a cam 138 by a spring 139, hooked to a rear extension 140 and to the frame or to be bolted to the frame through a hole 141 with its roller out of contact with the cam 138, according as it is desired to collect and fold away the lengths or sheets separately or to collect and fold two lengths upon each other. The left-hand run of the tapes 112 passes round cylinders 114 and 115 and partly round cylinder 113.

Assuming, first, that the lengths are to be collected and folded separately, and, referring more particularly to Figs. 10 to 13, the lever 136 is bolted to the frame, whereby the cam 119 will be held fixed in position to open the grippers 117 at every revolution. When the leading end of the perforated web reaches the position shown in Fig. 10, the projection 124 nips it against cylinder 113, breaks the tags, and severs the length, owing to the greater surface speed of the cylinders. The tapes 112 carry the length farther around on cylinder 113 until the projection 125 presses the leading edge into the bight of the grippers 117, which have in the meantime been opened by the roller 120 running up the elevation 142 of the cam 118. Simultaneously the roller 120 drops into the recess beyond 142 (see Fig. 11) and allows spring 122 to close the grippers 117 on the sheet, which is then carried around on cylinder 113 until the blade 123 tucks its middle into the light of the gripper-blade 126 or 127, which coact in turn with the blade 123, the cam 128 being arranged to close these latter gripper-blades on the paper against the action of their springs 131 or 132, so as to receive and fold the length of paper and strip the same from cylinder 113, the grippers 117 being simultaneously opened to release the paper by the roller 120 running on to the cam 119, Fig. 12. Fig. 13 shows the operation a little farther advanced, with the folded sheet being carried away by the grippers of cylinders 116 and the grippers 117 just closing on the succeeding sheet.

When it is desired to collect one length or sheet on top of another, instead of folding each length separately the lever 136 is unbolted from the frame and allowed to rest with its roller on the cam 138, and one of the gripper-blades 126 127 is put out of action in any ordinary way. It will be evident that as cylinder 113 makes two revolutions for one of cylinder 116 and cam 138 the cam 119 will now be caused by levers 136 133 and cam 138 to rise out of its operative position during the next revolution of cylinder 113. Consequently the cam 119 only opens the grippers 117 once in two revolutions to release the sheet at the point where the gripper-blades of cylinder 116 coincide with the folding-blade 123. Grippers 117 therefore retain their hold on the sheet until they are opened by the elevation 142 of cam 118 to receive the lead-

ing edge of the succeeding sheet, which is fed by the tapes 112 and is tucked into the bight of these grippers by the projection 125, as before, the grippers 117 immediately closing and carrying the two superposed sheets 70 round until the blade 123 tucks the middle of same into the operative gripper-blade of cylinder 116, by which time cam 119 has moved into its operative position and opens grippers 117 to release the sheets.

As the machine has to deal with different lengths of sheets, the mechanism must be capable of adjustment in such manner that the fold always comes in the middle of the length for the time being printed. To effect this, I 80 mount the folding-blade 123 on a carrier 143, pivoted on the axle 144 of cylinder 113. The end of this carrier is fastened by a bolt 145 to a gear-wheel 146, loose and adjustable on the end of cylinder 113. This gear-wheel (see 85 Fig. 14) is fastened to the end of cylinder 113 by bolts 147, passing through slots 148 in the gear-wheel. The gear-wheel 146 meshes with a gear-wheel 149 on the end of cylinder 116. By slackening the bolts 147 the folding-blades 123 can be shifted round on the axle 144, so as to increase or reduce the distance between it and the grippers 117 to suit the size of sheet being produced. As the gear-wheel 146 meshes with the gear-wheel 149, fixed on cylinder 116, it follows that when the blade 123 is moved round cylinder 116 is moved round correspondingly, and the relationship of the blade 123 to the gripper-blades of cylinder 116 remains 90 unaltered. It will be evident that instead of having the slots in the gear-wheel 146 they may be in the cylinder end or be otherwise arranged to obtain the same result. The motion is transmitted from cylinder 114 to 95 cylinder 113, and thence to cylinder 115 by gear-wheels 150 151 152 on the shafts of the respective cylinders.

It will be understood that I may employ folding mechanism constructed as just described in the delivery mechanism of any form of web-printing apparatus dealing with different lengths of printed sheets or products, whether the same be severed from a longitudinally-folded web or from an unfolded web. Further, the sheets or lengths may be entirely severed before passing to the said folding apparatus, in which case the cylinder 114, with nipping projections, may be dispensed with. Also if the apparatus is only 115 required to fold each sheet or length separately the movable cam 119 and its operating mechanism may be omitted and the fixed cam 118 be arranged to open the grippers 117 to release the sheet at the proper point in 120 each revolution.

The grippers of cylinder 116 carry the folded product round and transfer it to the grippers 153 of a conveyance-cylinder 154, which in turn transfer it to the grippers of a 130

final-delivery cylinder 155, which lays the product down on a traveling apron of bands 156 for removal by the attendant. The grippers of cylinders 154 and 155 are operated by cams or otherwise in any ordinary or suitable way, as will be well understood without further explanation.

The mechanism from and including the drawing-rollers 107 onward is driven from a vertical shaft 157, (see Fig. 7^a), which imparts its motion to the front perforating-cylinder 108 by bevel-wheels 158 159. The perforating-cylinders 108 108 are geared together by toothed wheels 160 and 161, and the motion is transmitted from them to the drawing-rollers 107 by a large gear 162 on the shaft of gear-wheel 160, and which meshes with a gear 163, which drives a gear 164 on the shaft of the front drawing-roller 107, the two drawing-rollers 107 being geared together at the opposite end by toothed wheels 165 166. (See Fig. 6.) The large gear 162 also drives a gear 167 on the back drawing-roller 111, these two rollers being also geared together at the other end by a pair of wheels, one of which, 168, is seen in Fig. 7^a. The gear 162 also drives the succeeding folding and delivery mechanism through intermediate gears 169 170 171, Figs. 6 and 9, the last of which drives the cylinders 113 114 115 116 through the gearing 150 151 152 146 149, before described. The motion is transmitted from gear-wheel 149 to the conveyance-cylinder 154 by a gear 172 on the corresponding side of the machine—*i. e.*, back of Fig. 9—and thence to the delivery-cylinder 155 by a gear 173 on the shaft of cylinder 155, from which the motion is communicated to the bands 156 in any ordinary way. The vertical shafts 48, 53, and 157 may be driven by any suitable mechanism, preferably arranged below the floor-line.

While I have gone into minute detail in describing the particular machine shown in Figs. 1 to 14 as illustrating one suitable way of putting the invention into practice, it will be understood that I do not confine myself to the exact details described, as they can be substantially varied without departing from the invention.

For certain classes of products of the type of printing machinery to which the invention chiefly relates it is sometimes necessary after cutting the web into sheets to give the paper one or sometimes two parallel cross-folds, followed by a longitudinal fold, and with or without a succeeding cross-fold, and for this purpose the invention includes the improved folding and delivering mechanism illustrated in Figs. 15 to 20. In this arrangement after the printed web has been cut into sheets, for example, by any of the types of cutting mechanisms before described the sheets or lengths 207 are carried forward between tapes 206 or otherwise to a folding-

cylinder 208, provided with conveying-grippers 209 and a folding-blade 210. The grippers 209 seize the leading edge of the sheet and carry it around until the blade 210 tucks its middle into the bight of the grippers 211 of a second cylinder 212, as shown in Fig. 18. Cylinder 212 also has a folding-blade 213. The grippers 211 carry the halved sheet around on cylinder 212, and the blade 213 is adapted to tuck the middle of the already-halved sheet into grippers 214 of a third cylinder 215, as seen in Fig. 19. The grippers 214 can be rendered inoperative in certain cases, as mentioned later; but we will first consider them to be operative, and the sheet will thus have received two parallel cross-folds. The grippers 214 carry the sheet around and deliver it between runs of double endless tapes 216, one set of which passes around cylinder 215 and a roller 216^a and the other round tape-rollers 216^b 216^b. These tapes carry the folded sheet on between a chopper-folder 217 of any known or suitable construction and its coöperating pair of folding-rollers 218. (See Fig. 16, 90 which is at right angles to Fig. 15.) Stops of any ordinary or suitable kind may be provided for the sheet above the rollers 218 to arrest its motion and insure accurate folding. The chopper-folder 217 presses the center 95 line of the sheet into the grip of its rollers 218, and thus gives the sheet a longitudinal middle fold. Over the rollers 218 218 pass another set of double endless tapes 219 219, which carry the folded product on between a second chopper-folder 220 and a coöperating pair of folding-rollers 221. This chopper-folder 220 can be put out of action, if desired. Assuming this to be done and the sheet to have previously received two parallel folds 105 and a longitudinal fold, as explained, the sheet will pass in between the tapes 219, which discharge it onto a delivery-fly 222, by which it is finally delivered onto a run of tapes 223 or otherwise. Figs. 18 and 19 show the action 110 of the folding-cylinders 208, 212, and 215 in imparting the two cross-folds. In Fig. 18 the middle of a sheet is being tucked by the blade 210 into the grippers 211, and in Fig. 19 the blade 213 is tucking the middle of the 115 folded sheet into the grippers 214, while the grippers 209 are carrying a fresh sheet around on cylinder 208.

If it is required to give the sheet one cross-fold followed by a longitudinal fold and then another cross-fold, the grippers 214 of cylinder 215 can be rendered inoperative in the usual way, and conveying-grippers 223^a then take the once-folded sheet from the grippers 211 (see Fig. 20) and deliver it to the tapes 216. These 125 carry it onto the chopper-folder 217, which gives it a longitudinal fold as before and pass it on between the tapes 219 to the second chopper-folder 220, which is in this case rendered operative, and consequently gives the 130

product a cross-fold by pressing it into the grip of its rollers 221, from which it is delivered by tapes 221^a to a second delivery-fly 224 and run of tapes 225 or otherwise. If desired, the chopper-folder 217 can also be adapted to be put out of operation according to the particular class of product to be produced.

For driving the cylinders, tapes, and rollers and operating the various grippers and chopper-folders of this folding mechanism the devices usually employed for such purposes may be adopted in a manner which will be well understood by those skilled in the art.

To enable the apparatus to deal with different lengths of sheets, the grippers 209 and blade 210 are adjustable relatively to each other, as are also the grippers 211 and blade 213. The folding blade and grippers of cylinder 208 are also adjustable with respect to those of cylinder 212, and the folding-blade of cylinder 212 is adjustable with respect to the folding-gripper 214 of cylinder 215. This may be effected by mounting the blades 210 and 213 and the rod which carries the gripper 211 on arms pivotally mounted on the shafts of their respective cylinders and adjustable by slots and bolts.

In the preferred arrangement the cylinders 208, 212, and 215 are geared together, and the means for adjusting the folding blades and grippers of cylinders 208 and 212 are so devised that the adjustment of the blade or gripper which is moved to effect the adjustment is communicated to the gear-wheel of the corresponding cylinder, and as the three cylinders are geared together they are turned or adjusted to an extent corresponding with that of the particular blade or gripper moved, so that the relationship of the operative members of one cylinder remains unaltered with respect to those of the others in a similar manner to that described with reference to Figs. 10 to 14. Fig. 17 will suffice to show how this may be carried into effect. This figure represents so much of the cylinder 208 in section as is necessary to show the adjustment of the folder-blade 210. This blade is carried by an arm at each end of the cylinder, these arms being pivotally mounted on the axle 226. The arm 227 at the end near the gear-wheel is formed with a segmental slot 228. Bolts 229 are passed through this slot and through a hole in the end of the cylinder and a segmental slot in the gear-wheel. The gear-wheel 230 is loose on the axle 226, and the slotted arm 227 is connected to it by the end of the folder-blade rod extending through the arm and gear-wheel and being secured by a nut, as at 231, or otherwise. The circumference and end of the cylinder are cut away, as at 232 233, for a suitable distance to allow the blade 210 to be turned within the required limits of adjustment.

To adjust the folding-blade 210 with respect

to the grippers 209, the bolts 229 are slackened and the blade is turned to the desired extent. Thus while the cylinder remains stationary the blade and gear-wheel are turned together and the other cylinders are turned to a corresponding extent. When the adjusting-slot is thus provided in the arm, the cylinder end is also preferably connected to the gear-wheel by other bolt-and-slot connections to insure a good drive.

The grippers 211 and folding-blade 213 are mounted on the axle of cylinder 212 and secured to the gear-wheel 234 in a similar way to the blade 210. Thus the blade 213 and grippers 211 can be relatively adjusted to the desired extent.

When it is required to use the grippers 223^a instead of the gripper-blade 214, as above mentioned, it will be necessary to turn the grippers 223^a around, so that they shall coat with the gripper 211. For this purpose the grippers 223^a are preferably fixed with respect to their cylinder, and this is adjustably connected to its gear-wheel by a bolt-and-slot connection, so that the cylinder 215 can be turned without moving its gear-wheel.

The form of delivery mechanism just described may be employed in the machine of Figs. 1 to 14 in place of that shown in these figures. In this case the cutting mechanism would, for example, be disposed immediately after the associating-rollers 92 93 94, and the fold-former 106 would be dispensed with, the two-ply web being thus cut into sheets and fed onto the cylinders 208, 212, and 215.

Figs. 21 to 23 illustrate an improved form of pasting mechanism which in many cases can be used with advantage in the machinery described and shown and also in web-printing machinery generally. This mechanism might, for example, be mounted in proximity to one of the registering-rollers 66 67, so as to apply a strip of paste to the half-web passing over said roller, so that when the half-webs are afterward associated they will be attached together by the paste strip.

235 is a paste-containing cylinder driven through any convenient gearing and mounted in suitable bearings in the machine-framing. This cylinder has a longitudinal slot 236, in which is mounted a pasting rod or roller 237. This rod is rotated slowly on its axis during the revolution of the cylinder 235. In the arrangement shown this is effected by a gear-wheel 238, fixed to the frame of the machine and gearing with a miter-wheel 239 on a miter-shaft 240, which drives a worm-wheel 241 on the pasting-roller 237 by a worm 242. The rod is thus made to revolve slowly as the pasting-cylinder rotates. By the employment of a cylinder mounted and arranged as described the web can be lapped around it with sufficient tension to insure perfect contact with the past-

ing-roller 237, so that a strip of paste will be reliably applied to the web by this roller as the web travels around the cylinder 235 without any necessity for a coating revolving blade or other means for pressing the web against the pasting-roller 237 when this reaches the pasting position.

243 243 are adjustable scrapers or strickles which can be set to allow the rod 237 to carry around the required amount of paste.

Fig. 23 shows suitable means for filling the cylinder 235, consisting of a hopper 244, fitted into the end of the hollow axle 245 of the cylinder through a stuffing-box 246, the axle being formed with an opening or openings 247. The rod 237 may be rotated intermittently, if desired, instead of continuously.

The devices for drying the freshly-printed sheets are not claimed in this application; but it is not to be understood therefrom that I waive my right to claim the same in a separate application.

What I claim as my invention, and desire to secure by Letters Patent, is—

1. In rotary web-printing machinery, looping-rollers for the web disposed respectively in advance of one printing-couple and beyond a subsequent printing-couple, said rollers being coupled together by side rods or carriers, in combination with means for reciprocating said rods or carriers and looping-rollers to simultaneously loop up paper in advance of the printing-couples and loop down paper beyond the printing-couples during passage of blank portions of the printing-surface opposite the printing-point and to give up paper in advance of the couples and loop up paper beyond the couples when the printing and impression surfaces are in contact, said reciprocating means being adapted to cause the said rollers during the passage of the blank portions of the printing-surface opposite the printing-point to descend with a speed gradually increasing to a maximum and thereafter to ascend with a gradually-increasing speed, whereby during such passage of the blank portions of the printing-cylinders the web is first gradually arrested, then reversed, and then restarted forwardly at a suitable surface speed to be nipped between the printing and impression surfaces, substantially as described.

2. In rotary web-printing machinery, looping-rollers for the web disposed respectively in advance of one printing-couple and beyond a subsequent printing-couple, said rollers being coupled together by side rods or carriers, in combination with interchangeable cams adapted to effect reciprocation of said rods or carriers and looping-rollers, to simultaneously loop up paper in advance of the printing-couples and loop down paper beyond the printing-couples during passage of blank portions of the printing-surface opposite the printing-point, and to give up paper in ad-

vance of the couples and loop up paper beyond the printing-couples when the printing and impression surfaces are in contact, said cams being adapted by their form to cause the said rollers during the passage of the blank portions of the printing-surface opposite the printing-point to descend with a speed gradually increasing to a maximum and thereafter to ascend with a gradually-increasing speed, whereby during such passage of the blank portions of the printing-cylinders the web is first gradually arrested, then reversed, and then restarted forwardly at a suitable surface speed to be nipped between the printing and impression surfaces, substantially as described.

3. In rotary web-printing machinery, looping-rollers for the web disposed respectively in advance of one printing-couple and beyond a subsequent printing-couple, said rollers being coupled together by side rods or carriers, in combination with interchangeable side cams adapted to effect reciprocating of said rods or carriers substantially direct to simultaneously loop up paper in advance of the printing-couples and loop down paper beyond the printing-couples during passage of blank portions of the printing-surface opposite the printing-point, and to give up paper in advance of the couples and loop up paper beyond the printing-couples when the printing and impression surfaces are in contact, said cams being adapted by their form to cause the said rollers during the passage of the blank portions to the printing-surface opposite the printing-point to descend with a speed gradually increasing to a maximum and thereafter to ascend with a gradually-increasing speed, whereby during such passage of the blank portions of the printing-cylinders the web is first gradually arrested, then reversed, and then restarted forwardly at a suitable surface speed to be nipped between the printing and impression surfaces, substantially as described.

4. In rotary web-printing machinery, looping-rollers for the web, disposed respectively in advance of one printing-couple and beyond a subsequent printing-couple, side rods whereby said rollers are coupled together, sliding blocks on said rods and cam-rollers on said blocks, interchangeable side cams whereon said cam-rollers work, springs whereby said cam-rollers are held in contact with the cams, and gear-wheels driven at the same number of revolutions as the printing-couples and to which said cams are removably secured, said cams being adapted to effect reciprocation of said rods to simultaneously loop up paper in advance of the printing-couples and loop down paper beyond the printing-couples during passage of blank portions of the printing-surface opposite the printing-point, and to give up paper in advance of the couples and loop up paper be-

yond the printing-couples when the printing and impression surfaces are in contact, said cams being further adapted by their form to cause the said rollers during the passage of the blank portions of the printing-surface opposite the printing-point to descend with a speed gradually increasing to a maximum and thereafter to ascend with a gradually-increasing speed, whereby during such passage of the blank portions of the printing-cylinders the web is first gradually arrested, then reversed, and then restarted forwardly at a suitable surface-speed to be nipped between the printing and impression surfaces, substantially as described.

5. In web-printing machinery for producing printed pages of variable length, printing and impression cylinders, and web-looping rollers disposed before and beyond said printing and impression cylinders, in combination with a cam adapted to reciprocate the looping-rollers with a variable motion such that during the passage of blank portions of the printing-surface in contiguity to the web, this is first gradually arrested, then slightly reversed, and then gradually restarted forward and caused to travel at a surface-speed approximately equal to that of the printing-surface when this again grips the web.

30 6. In the delivery mechanism of rotary web-printing machinery capacitated to produce different sizes of printed sheets, a pair of cylinders arranged to be driven at a surface-speed equal to that of the web when the machine is producing the smallest length of page, and spaced apart to allow the web to pass freely through, one having one or more perforating-blades and the other one or more bolsters or members coacting therewith to 35 nip and perforate the web, whereby when sizes of more than minimum length are produced the web is looped before said cylinders, in combination with rollers arranged to draw the web from said cylinders and to be driven 40 at a speed sufficient to take up the loop, and another pair of cylinders spaced apart and arranged to be driven at a higher surface-speed than the web, one of these latter cylinders having a projection adapted to nip the 45 web and break the tags between the perforations, substantially as described.

7. In the delivery apparatus of web-printing machinery mechanism for holding variable lengths severed from a printed web, said mechanism comprising a cylinder having collecting-grippers and a folding-blade, means for opening said collecting-grippers at a given point in the revolution of said cylinder to release the folded product, means for closing said grippers on the product at a point in their revolution beyond such releasing-point, tapes adapted to hold the product on said cylinder until it reaches said gripping-point, a second cylinder coacting with the first and 55 provided with a member adapted to press the

leading edge of each length into the bight of said grippers when same are open, a third cylinder having a folding-gripper adapted to coact with the folding-blade of the first cylinder to fold and strip the product therefrom when 70 said collecting-grippers open at the releasing-point and means for relatively adjusting the folding-blade and conveying-grippers of the first cylinder, according to the length to be dealt with, substantially as described. 75

8. In the delivery apparatus of web-printing machinery, mechanism for folding variable-sized lengths severed from a previously perforated printed web, said mechanism comprising four coacting cylinders adapted to be 80 driven at a greater surface speed than the web, collecting-grippers and a folding-blade on the said first cylinder, means for opening said collecting-grippers at a given point in the revolution of their cylinder to release the 85 folded product, means for closing said grippers on the product to grip the same at a point in their revolution beyond such releasing-point, a projection on the second cylinder adapted to press the perforated web 90 against the first cylinder and thereby sever a length therefrom, tapes adapted to hold the product on said first cylinder until it reaches said gripping-point, a projection on the third cylinder adapted to press the leading edge of 95 each length into the bight of said grippers when same are open, a folding-gripper on said fourth cylinder adapted to coact with the folding-blade of the first cylinder to fold and strip the product therefrom when the collecting-grippers of the first cylinder open at their said releasing-point, and means for 100 relatively adjusting the folding-blade and conveying-grippers of the first cylinder according to the length of product to be dealt with, substantially as described. 105

9. In the delivery apparatus of web-printing machinery, mechanism for folding variable lengths severed from a printed web, said mechanism comprising a cylinder having 110 spring-controlled collecting-grippers and a folding-blade, a cam device coacting with said grippers to open the same at a given point in the revolution of said cylinder to release the folded product, to hold said grippers open for a succeeding portion of the revolution of said cylinder and to then allow said grippers to close, tapes adapted to hold the product on said cylinder while the grippers are open, a second cylinder having a 115 projection adapted to press the leading edge of each length into the bight of said open grippers, a third cylinder having a spring-controlled folding-gripper adapted to coact with the folding-blade of the first cylinder to fold and strip the product therefrom when said collecting-grippers open at the releasing-point, a cam coacting with said folding-gripper to cause the same to be thus opened, and means for 120 relatively adjusting the folding- 125

130

blade and conveying-grippers of the first cylinder according to the length of product to be dealt with, substantially as described.

10. In the delivery apparatus of web-printing machinery, mechanism for folding variable lengths severed from a printed web and capacitated to fold away two superposed lengths at a time, said mechanism comprising a cylinder having collecting-grippers and a folding-blade, means for opening said collecting-grippers at a given point once in every alternate revolution of said cylinder to release the product, means for opening said grippers once in every revolution at a point beyond said releasing-point, and thereafter closing the same to grip the product, tapes adapted to hold the successive lengths on said cylinder until the same reach said gripping-point, a second cylinder coacting with the first and provided with a member adapted to press the leading edge of each length into the bight of said grippers when same are thus opened in each revolution, a third cylinder having a folding-gripper adapted to coact with the folding-blade of the first cylinder to fold and strip the product therefrom when said collecting-grippers open at their said releasing-point, and means for relatively adjusting the folding-blade and conveying-grippers of the first cylinder, according to the length to be dealt with, substantially as described.

11. In the delivery apparatus of web-printing machinery, mechanism for folding variable lengths severed from a printed web and capacitated to fold away two superposed lengths, said mechanism comprising a cylinder having spring-controlled collecting - grippers and a folding - blade, a movable cam 35 adapted to coact with said grippers, mechanism for moving said cam at every alternate revolution of said cylinder into operative position to cause said grippers to open to release the product at a given point of their 40 revolution, a second cam coacting with said grippers to open the same once in every revolution beyond said releasing-point and thereafter allowing the same to close to grip the product, tapes adapted to hold the successive 45 lengths on said cylinder until they reach said gripping-point, a second cylinder coacting with the first and having a member adapted to press the leading edge of each length into the bight of said grippers when same are thus 50 lengths on said cylinder until they reach said gripping-point, a second cylinder coacting with the first and having a member adapted to press the leading edge of each length into the bight of said grippers when same are thus 55 opened in each revolution, a third cylinder having spring-controlled folding - grippers adapted to coact with the folding-blade of the first cylinder to fold and strip the product therefrom when said collecting - grippers 60 open at their said releasing-point, and means for relatively adjusting the folding-blade and conveying-grippers of the first cylinder, according to the length to be dealt with, substantially as described.

65 12. In the delivery apparatus of web-

printing machinery, mechanism for folding variable lengths severed from a printed web, and capacitated to fold away superposed lengths, said mechanism comprising a cylinder having spring-controlled collecting-grippers and a folding-blade, a movable cam adapted to coact with said grippers, mechanism for moving said cam at every alternate revolution of said cylinder into operative position to cause said grippers to open to release the product at a given point of their revolution, a second cam coacting with said grippers to open the same once in every revolution beyond said releasing-point and thereafter allowing the same to close to grip the product, tapes adapted to hold the successive lengths on said cylinder until they reach said gripping-point, a second cylinder coacting with the first and having a member adapted to press the leading edge of each length into the bight of said grippers when same are thus opened in each revolution, a third cylinder having spring-controlled folding-grippers adapted to coact with the folding-blade of the first cylinder to fold and strip the product therefrom when said collecting-grippers open at their said releasing-point, and means for relatively adjusting the folding-blade and conveying-grippers of the first cylinder, according to the length to be dealt with, and means for holding said movable cam out of its operative position with regard to the said conveying-grippers, whereby the lengths may be collected and folded away separately, substantially as described.

13. In the delivery apparatus of web-printing machinery, mechanism for folding variable lengths severed from a printed web, and capacitated to fold away two superposed lengths, said mechanism comprising a cylinder having spring-controlled collecting-grippers and a folding-blade, a movable cam adapted to coact with said grippers, mechanism for moving said cam at every alternate revolution of said cylinder into operative position to cause said grippers to open to release the product at a given point of their revolution, a second cam coacting with said grippers to open the same once in every revolution beyond said releasing-point and thereafter allowing the same to close to grip the product, tapes adapted to hold the successive lengths on said cylinder until they reach said gripping-point, a second cylinder coacting with the first and having a member adapted to press the leading edge of each length into the bight of said grippers when same are thus opened in each revolution, a third cylinder having spring-controlled folding-grippers adapted to coact with the folding-blade of the first cylinder to fold and strip the product therefrom when said collecting-grippers open at their said releasing-point, said second and third cylinders being geared to the first, the folding-blade of the first cylinder being ad-

justably mounted on the axle of the first cylinder and connected to the gear-wheel thereof, and an adjustable connection between said gear-wheel and cylinder whereby the 5 adjustment of said folding-blade is communicated to the second and third cylinders and means for holding said movable cam out of its operative position with regard to said conveying-grippers, whereby the lengths may be 10 folded away separately, substantially as described.

14. In the delivery apparatus of web-printing machinery, mechanism for folding variable lengths severed from a printed web and 15 capacitated to fold away two superposed lengths, said mechanism comprising a cylinder having spring-controlled collecting-grippers and a folding-blade, a second cylinder adapted to be driven at half the number of 20 revolutions of the first and having two diametrically opposite spring-controlled folding-grippers adapted to coact in turn with said folding-blade, a movable cam coacting with said conveying-grippers, a rocking carrier 25 whereon said movable cam is mounted, a rotary cam on the shaft of said second cylinder, adapted to rock the said carrier and bring said movable cam into operative position once in every alternate revolution of said first cylinder 30 to cause said conveying-grippers to open and release the product at a given point of their revolution when the folding-grippers of the second cylinder coact with said folding-blade, a fixed cam coacting with said conveying-grippers to open the same once in every revolution beyond said releasing-point and thereafter allowing them to close and grip 35 the product, tapes adapted to hold the successive lengths on said first cylinder until they reach said gripping-point, a third cylinder coacting with the first and having a member adapted to press the leading edge of each length into the bight of said conveying-grippers when same are thus opened in each revolution, a fixed cam coacting with the folding-grippers of said second cylinder whereby the same are closed to coact with said folding-blade to fold and strip the product from the first cylinder when the said gripper-blades coact with said folding-blade, the folding-blade and conveying-grippers of the first cylinder being relatively adjustable according to the length to be dealt with, one of said folding-grippers being 40 adapted to be put out of action and said rocking carrier to be secured with its cam out of operative position, whereby the lengths 45 may be folded away separately, substantially as described.

55 15. In the delivery apparatus of web-printing machinery, mechanism for folding variable lengths severed from a printed web and capacitated to fold away two superposed lengths, said mechanism comprising a 60 cylinder having spring-controlled collecting-grippers and a folding-blade, a second cylinder adapted to be driven at half the number of revolutions of the first and having two diametrically opposite spring-controlled folding-grippers adapted to coact in turn with 65

said folding-blade, a movable cam coacting with said conveying-grippers, a rocking carrier whereon said movable cam is mounted, a rotary cam on the shaft of said second cylinder, adapted to rock the said carrier and bring said movable cam into operative position once in every alternate revolution of said first cylinder to cause said conveying-grippers to open and release the product at a given point of their revolution when the folding-grippers of the second cylinder coact with said folding-blade, a fixed cam coacting with said conveying-grippers to open the same once in every revolution beyond said releasing-point and thereafter allowing them to close and grip the product, tapes adapted to hold the successive lengths on said first cylinder until they reach said gripping-point, a third cylinder coacting with the first and having a member adapted to press the leading edge of each length into the bight of said conveying-grippers when same are thus opened in each revolution, a fixed cam coacting with the folding-grippers of said second cylinder whereby the same are closed to coact with said folding-blade to fold and strip the product from the first cylinder when the said gripper-blades coact with said folding-blade, the folding-blade and conveying-grippers of the first cylinder being relatively adjustable according to the length to be dealt with, one of said folding-grippers being adapted to be put out of action and said rocking carrier to be secured with its cam out of operative position, whereby the lengths 100 may be folded away separately, substantially as described.

16. In the delivery apparatus of web-printing machinery, mechanism for folding variable lengths severed from a printed and perforated web and capacitated to fold away two superposed lengths, said mechanism comprising four coacting cylinders adapted to be driven at a greater surface speed than the web, spring-collecting grippers and a folding-blade on the first cylinder, a movable cam adapted to coact with said grippers, mechanism for moving said cam at every alternate revolution of the first cylinder into operative position to cause said grippers to open and release the product at a given point of their revolution, a second cam coacting with said grippers to open the same once every revolution beyond said releasing-point and thereafter to allow same to close and grip the product, a projection on the second cylinder adapted to press the perforated web against the first cylinder and thereby sever a length therefrom, tapes adapted to hold the product on said first cylinder until it reaches said gripping-point, a projection on the third cylinder adapted to press the leading edge of each length into the bight of said grippers when same are open, spring-folding grippers on said fourth cylinder adapted to coact with 125

the folding-blade of the first cylinder to fold and strip the product therefrom when said collecting-grippers open at their releasing-point, and means for relatively adjusting the 5 folding-blade and conveying-grippers of the first cylinder according to the length of product, substantially as described.

17. In the delivery apparatus of web-printing machinery, mechanism capacitated 10 to fold variable lengths severed from a printed web, said mechanism comprising three co-operating folding-cylinders, the first having conveying-grippers and a folding-blade, the second a folding-gripper adapted to coact 15 with said folding-blade and also a folding-blade, and the third cylinder having a folding-gripper adapted to coact with the folding-blade of the second cylinder and conveying-grippers adapted alternatively to coact with 20 the folding-gripper of the second cylinder, the folding-blades and grippers of the first two cylinders being relatively adjustable according to the length of product, a chopper-folder with coacting folding-rollers, and traveling tapes adapted to convey the product from said third cylinder between said chopper-folder and rollers; a second set of traveling tapes adapted to receive the folded product from said chopper-folder and rollers and 25 30 to convey it to a delivery device; a second chopper-folder and coacting folding-rollers at right angles to the first and between which said second set of traveling tapes pass to a second delivery device, said second chopper-folder being adapted to be put out of action, whereby one or two parallel cross-folds followed by a longitudinal fold and with or without a succeeding cross-fold can be given to the product, substantially as described.
- 35 40 45 18. In the delivery apparatus of web-printing machinery, mechanism capacitated to fold variable lengths severed from a printed web, said mechanism comprising three co-operating folding-cylinders, the first having conveying-grippers and a folding-blade, the second a folding-gripper adapted to coact with said folding-blade, and also a folding-blade, and the third cylinder having a folding-gripper adapted to coact with the fold-

ing-blade of the second cylinder, and also 50 conveying-grippers adapted alternatively to coact with the folding-gripper of the second cylinder, the first cylinder being geared to the second and the second to the third, and the said folding-blades being adjustably 55 mounted on the axles of their respective cylinders and connected to their respective gear-wheels and adjustable connections between said gear-wheels and their respective cylinders whereby adjustment of the folding-blade of one cylinder is communicated to the other cylinders, a chopper-folder with coacting folding-rollers and traveling tapes adapted to convey the product from said third cylinder between said chopper-folder and rollers; a second set of traveling tapes adapted 60 to receive the folded product from said chopper-folder and rollers and to convey it to a delivery device; a second chopper-folder and coacting folding-rollers at right angles to the 65 first and between which said second set of traveling tapes pass to a second delivery device, said second chopper-folder being adapted to be put out of action, whereby one or two parallel cross-folds followed by a longitudinal fold and with or without a succeeding cross-fold can be given to the product, 70 substantially as described.

19. In the delivery apparatus of web-printing machinery, a rotary paste-containing 80 cylinder over which the web is adapted to be led, a longitudinal slot in said cylinder, a pasting-roller mounted in said slot, a worm-wheel on said pasting-roller, a miter-shaft provided with a worm gearing with said worm-wheel 85 and with a gear-wheel meshing with a gear rigidly mounted on a fixed part of the machine whereby the pasting-roller is positively rotated as the cylinder revolves, substantially as described.

In witness whereof I have hereunto signed my name in the presence of two subscribing witnesses.

ROBERT CUMMING ANNAND.
